US0D1058766S

(12) **United States Design Patent** (10) Patent No.: **US D1,058,766 S**
(45) Date of Patent: ** Jan. 21, 2025

(54) **SINK DRAIN STRAINER**

(71) Applicant: **Renxiong Song**, Yongzhou (CN)

(72) Inventors: **Renxiong Song**, Yongzhou (CN);
Liming Song, Yongzhou (CN)

(73) Assignee: **Renxiong Song**, Yongzhou (CN)

(**) Term: **15 Years**

(21) Appl. No.: **29/950,200**

(22) Filed: **Jul. 1, 2024**

(30) **Foreign Application Priority Data**

Jan. 3, 2024 (CN) 202430003090.4

(51) **LOC (15) Cl.** **23-01**

(52) **U.S. Cl.**

USPC **D23/261**; D23/260; D23/259

(58) **Field of Classification Search**

USPC D23/205-206, 213, 243, 249, 255,
D23/259-261, 263, 266, 269, 303, 358,

(57) **CLAIM**

The ornamental design for a sink drain strainer, as shown and described.

DESCRIPTION

FIG. 1 is a top perspective view of a sink drain strainer, showing our new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.
